UNITED STATES PATENT OFFICE

2,569,592

APPARATUS FOR POLISHING PRECIOUS STONES

Charles West, London, England, assignor to
 Henry Oliver and Lewi Stone, both of London,
 England

Application November 1, 1948, Serial No. 57,685
 In Great Britain November 4, 1947

8 Claims. (Cl. 51—229)

1

This invention relates to apparatus for polishing precious stones particularly diamonds, and to apparatus of the kind in which the dop for holding the stone is mounted in a head at the end of an arm or tang, which latter is so supported at its end remote from the head as to permit the head to swing downwardly under gravity so that the stone engages the flat face of a rotating polishing element and also permits the dop to be moved towards and away from the centre of rotation of the polishing member.

According to this invention an apparatus for polishing precious stones of the kind referred to comprises a flat faced member having its face parallel with that of the polishing element, an arm, a head at one end of the arm adapted to carry a dop, a fulcrum on said arm disposed away from the head and slideably engaging the face of said flat faced member permitting the arm to swing in an up and down direction, a stop or support rigidly fixed to said flat faced member and arranged to underlie said arm.

Means may be provided for securing said flat faced member to a bench which means permit adjustment of said member relatively to the bench to bring the flat face parallel with the polishing face.

For example the flat faced member comprises a metal plate and clamping bolts extending through holes in said plate and through plugs adjustably mounted in said bench, the heads of which plugs support said plate.

The aforesaid head embodies means for adjusting the position of the dop in an up and down direction. With this arrangement the support is initially adjusted so that the arm, when resting upon it, is parallel with the surface of the polishing disc, and the head is then adjusted so that when the stone is resting on the disc the arm is raised from the stop by an amount corresponding to the amount of cut required. Polishing will thus cease when the arm contacts with the stop.

The arm may be provided with two downwardly extending legs spaced apart in a direction across the length of the arm, which legs are arranged to rock on said support, and one of said locating faces is arranged to abut the side of one of said legs, while the other locating face is arranged to abut the side of the arm adjacent said stop.

The latter locating face may be provided by a pillar on which said stop is adjustably mounted, which pillar is carried by said support.

2

A warning device may be arranged to be operated by said arm coming into contact with said stop. For example a member resiliently mounted on said stop is arranged to be moved by the arm when approaching the stop so as to close contacts in a circuit with a warning device and with a source of supply.

The warning device may comprise an electric light mounted on said support.

10 The resiliently mounted member may comprise a lever, one end of which is arranged to be engaged by said arm and the other end of which may comprise one of a pair of electric contacts in circuit with the warning device, and a spring 15 may be arranged to urge the bell-crank lever to a limiting position in which the first said limb is slightly proud of said stop.

10 The aforesaid head may comprise a bearing in which may be rotated the stem of a bracket carrying the dop and the associated indexing mechanism for bringing different facets into a polishing position, which bearing is adjustable in an up and down direction. One of the purposes 20 of this bearing is to enable the face of the stone in contact with the disc to be brought into a position in which the grain of the stone is appropriately disposed in relation to the direction of rotation of the disc. It is important that the axis of this bearing shall be normal to the grinding surface, otherwise the adjustment of the bracket about said axis will adversely effect the setting of the facet being ground.

25 In order to enable the axis of the bearing to be set accurately at right angles to the surface of the grinding disc the aforesaid bearing member is mounted universally in said head so as to permit a limited pivotal adjustment in any direction, and means are provided for clamping the bearing member in an appropriate position.

30 The following is a description of one form of diamond-polishing device according to this invention, reference being made to the accompanying drawings, in which:

35 Figure 1 is a perspective view of the mounting for supporting the diamond holder or dop;

40 Figure 2 is a section through the head which receives the dop;

45 Figure 3 is a view looking from the right of Figure 1, showing the warning device;

50 Figures 4 and 5 are side elevations of the means for applying a load to the arm, and

55 Figure 6 is a section through loading device when in an operative position.

The holder or dop for the diamond or other stone to be cut is provided in known manner with a stem or bracket which is accommodated in a hollow bearing member 10 constituting a part of a head carried at the end of an arm or tang 11. The other end of the arm is provided with two downwardly-extending legs 12 spaced apart across the length of the arm, the lower ends of which legs are provided with projections 13 which may rock on a metal supporting plate 14 having holes 15 whereby it may be attached firmly to a bench. One of the legs is arranged to abut against an upstanding ledge 16 on the supporting plate 14. The side of the arm 11 remote from said ledge is arranged to abut against a pillar 17 carried by an arm 18 secured to the supporting plate by set screws 19. The pillar 17 carries a stop 20 which underlies the arm and is adjustable in an up-and-down direction, and this pillar is held in the adjusted positions by a grub-screw 21.

As will be seen from Figure 3, an end face of the stop 20 has pivotally mounted upon it a lever arm 22 which is urged by a wire spring 23 against a stop pin 24 in which position a pointed end 25 of the lever arm extends a short distance above the top face of the stop 20. The lower end of the lever arm 22 is arranged opposite an adjustable electric contact 26 on an arm 21 carried by an insulating block 28 secured to the part 18. The lever arm in engaging the contact 26 establishes a circuit in which a warning lamp 29 is energised by source of supply 30.

As will be seen from Figure 2, the end of the arm 11 is provided with a cup-shaped recess 31 having an aperture 32 at the bottom thereof. The head is provided with a spherical portion 33 which rests in said recess and with a flange 34 which overlies the arm. The flange is provided with a number of threaded holes engaged by set-screws 35 which extend through the arm, whereby the spherical part of the body may be clamped firmly in the recess.

The tubular bearing member 10 extends through a bore in the head so as to be a good sliding fit in the lower part of the bore 36, which bearing member is provided with an external key-way 37 which is engaged by a key 38 fixed in the head. The upper part of the bore is enlarged at 39 and the upper part of the bearing member is externally threaded at 40. This threaded part is encircled by a nut having a flange 41, and a boss 42, which latter is a rotating fit in the enlarged bore. The boss is provided with a circumferential groove of rectangular section which accommodates two parts of a split sleeve 43, each of which is provided with a conical depression 44 which may be engaged by the pointed end of a grub-screw 45, in the head, so as to draw the split sleeves downwardly, and with them the nut so that the flange rests snugly against the top of the head, thus preventing backlash.

The plate 14 may be mounted on the same bench 68 as the scathe 46 and it is important that the face of the plate shall be strictly parallel to the face of the scathe. Means are therefore provided for adjusting the position of the plate in relation to the bench. These means may comprise a nut 63 inset in the bench beneath each corner of the plate, each of which nuts receives an externally threaded hollow plug 64 having a domed head 65, on which the plate rests. Bolts

69 extend through the hollow plugs and bench and are provided with clamping nuts 66.

In setting up the device, the plugs 64 are adjusted to bring the plate accurately parallel to the surface of the scathe and the bolts tightened so as firmly to clamp the plate to the bore. The stop 20 is adjusted to such a position that when the arm 11 is resting upon it, the axis of the bearing member 10 is accurately at right-angles to the surface of the scathe by which the diamond is ground, which scathe is shown in chain lines at 46 in Figure 1, in this position the diamond is resting on the scathe. The amount by which the diamond is to be ground may then be set by twisting the flange 41 of the nut which may be graduated at 47 on its upper surface, which graduation co-operates with a pointer 48 on the arm. The arm is thus lifted a short distance from the stop 20, and the lever arm 22 is brought away from the contact 26 by the spring 23. Grinding then commences and the arm gradually lowers, and when the predetermined amount of grinding has been effected, the arm 11 will have swung the lever 22 into engagement with the contact 26 and the warning light 29 is then brought into operation. With this arrangement when the feet 13 are moved over the accurately ground face of the plate 14 the axis of the bearing member 10 is maintained accurately at right-angles to the scathe for all positions of the arm. While the arm is prevented from lateral movement by the ledge 16 and pillar 17 which movement might otherwise take place due to the rotation of the scathe.

35 The arm 11 may be loaded either by placing weights on top of it, or it may be more accurately loaded by means of a loading arm 49 along which a mass 50 may be adjusted. The loading arm is pivoted at 51 and has pivotally secured at 54 on either side thereof, two upwardly-extending members 52, 53. The member 53 is provided with a peg 55 which when the two members have been swung into the position Figure 4 may be pushed inwardly to overlie a ledge 56 secured to the underside of the arm 11, the peg may be retained in the operative and inoperative positions by a spring-detent 67. The peg is provided with a manipulating head 57. The peg in its outermost position is arranged to be clear of the ledge 56.

55 The lower end of the member 52 is provided with a camming piece 58 which engages an abutment 59 on the part 18 whereby the loading arm 49 may be raised and the peg brought above the ledge 56 as shown in Figure 4. In this position, when the peg is in its outermost position, the head 57 lies in the path of movement of the upper portion of the member 52. As soon as the peg has been pushed inwardly, the member 52 60 may be swung into a position in which the camming member 58 is no longer in contact with the abutment 59 whereupon the load is transferred to the arm 11. The member 52 is provided with a manipulating tag 60, and a locating piece 61 65 for the other member 53, which enables the two members 52 and 53 to swing together so as to bring the peg entirely clear of the arm 11.

The member 18 is provided with recesses 62 for receiving the stones before or after grinding and the recesses may be covered by a plate 63 arranged to clip on to the member 18.

I claim:

1. An apparatus for use with a flat faced polishing element for polishing precious stones, 75 which apparatus comprises a flat-faced member,

adjustable securing means for holding that member on a bench whereby its face may be brought parallel with the face of the polishing element, an arm, a head at one end of the arm, a dop carried by said head, a fulcrum on said arm disposed away from the head and slidably engaging the face of said flat-faced member permitting the arm to swing in an up-and-down direction, a support rigidly fixed to said flat-faced member and having a part underlying said arm.

2. An apparatus for use with a flat-faced polishing element for polishing precious stones which apparatus comprises a bench, a number of plugs adjustable in relation to the surface of the bench, a flat metal plate resting on said plugs which plate and plugs have registering holes, clamping bolts extending through said holes, an arm, a head at one end of the arm, a dop carried by said head, a fulcrum on said arm disposed away from the head and slidably engaging the face of said flat-faced member permitting the arm to swing in an up-and-down direction, a support rigidly fixed to said flat-faced member and having a part underlying said arm.

3. An apparatus for use with a flat-faced polishing element for polishing precious stones which apparatus comprises a flat-faced member, adjustable securing means for holding that member on a bench whereby its face may be brought parallel with the face of the polishing element, an arm, a head at one end of the arm, a dop carried by said head, a fulcrum on said arm disposed away from the head and slidably engaging the face of said flat-faced member permitting the arm to swing in an up-and-down direction, a support rigidly fixed to said flat-faced member, a part underlying said arm and adjustable in an up-and-down direction on said support.

4. An apparatus for use with a flat-faced polishing element for polishing precious stones, which apparatus comprises a flat-faced member, adjustable securing means for holding that member on a bench whereby its face may be brought parallel with the face of the polishing element, an arm, a head carried at one end of the arm, means for adjusting said head in an up-and-down direction relatively to said arm, a dop carried by said head, a fulcrum on said arm disposed away from the head and slidably engaging the face of said flat-faced member permitting the arm to swing in an up-and-down direction, a support rigidly fixed to said flat-faced member and having a part underlying said arm.

5. An apparatus for use with a flat-faced polishing element for polishing precious stones which apparatus comprises a flat-faced member, adjustable securing means for holding that member on a bench whereby its face may be brought parallel with the face of the polishing element, an arm, a head at one end of the arm, a dop carried by said head, a fulcrum on said arm disposed away from the head and slidably engaging the face of said flat-faced member permitting the arm to swing in an up-and-down direction, a pillar rigidly fixed to the flat-faced member on one side of the arm, a support on said pillar underlying said arm, an upstanding ledge on the flat-faced member on the other side of said arm, which ledge and pillar are adapted to constrain said arm to move rectilinearly towards and away from said polishing element.

6. An apparatus for use with a flat-faced polishing element for polishing precious stones

which apparatus comprises a flat faced member, adjustable securing means for holding that member on a bench whereby its face may be brought parallel with the face of the polishing element, an arm, a head at one end of said arm, a mounting for said head adapted to permit angular adjustment of the head about a vertical axis, a dop carried by said head, a fulcrum on said arm disposed away from said head and slidably engaging the face of said flat faced member permitting the arm to swing in an up-and-down direction, a support rigidly fixed to said flat-faced member and having a part underlying said arm.

7. An apparatus for use with a flat-faced polishing element for polishing precious stones which apparatus comprises a flat faced member, adjustable securing means for holding that member on a bench whereby its face may be brought parallel with the face of the polishing element, an arm, a head at one end of the arm, a dop carried by said head, a fulcrum on said arm disposed away from the head and slidably engaging the face of said flat-faced member permitting the arm to swing in an up-and-down direction, a support rigidly fixed to said flat-faced member and having a part underlying the said arm, a warning device, and a transmission between the arm and support adapted to magnify the movement of the arm and to actuate the warning device when the arm contacts with the underlying part of the support on which it freely rests.

8. An apparatus for use with a flat-faced polishing element for polishing precious stones which apparatus comprises a flat-faced member, adjustable securing means for polishing that member on a bench whereby the face may be brought parallel with the face of the polishing element, an arm, a head at one end of the arm, a dop carried by said head, a fulcrum on said arm disposed away from the head and slidably engaging the face of said flat-faced member permitting the arm to swing in an up-and-down direction, a support rigidly fixed to said flat-faced member and having a part underlying said arm, a lever pivotally mounted on said flat-faced member, a mass adjustable along said lever, an abutment on the lever overlying a part of the arm and cam means for moving the lever and abutment slowly into the path of movement of the arm.

CHARLES WEST.
